EDWIN C. HENN, OF CLEVELAND, OHIO.

SPARK-PLUG.

1,073,043.

Specification of Letters Patent. Patented Sept. 9, 1913.

Application filed January 4, 1912. Serial No. 629,417.

To all whom it may concern:

Be it known that I, EDWIN C. HENN, a citizen of the United States, residing at Cleveland, in the county of Cuyahoga and State of Ohio, have invented certain new and useful Improvements in Spark-Plugs, of which the following is a specification:

This invention relates to ignition or spark plugs for internal combustion engines, the object of the invention being to provide an improved spark plug having a large firing or sparking area in which the danger of corrosion is reduced to a minimum and the accumulation of oil and carbon deposits largely prevented, the plug being a comparatively simple and inexpensive one to produce.

In the drawings accompanying and forming part of this specification, Figure 1 is a partly vertical sectional view of this improved plug; Fig. 2 is a side elevation thereof; and Fig. 3 is an end view illustrating the electrodes.

Similar characters of reference indicate corresponding parts in the figures of the drawings.

So far as the general construction of the plug is concerned it may be of any desired form or structure. In the present instance it is illustrated as comprising a centrally bored insulating core 2, which may be of porcelain or other material, surrounded by a chambered casing 3 which is externally threaded, as at 4, for connection with the apparatus or engine in which it is to be used and internally threaded, as at 5, for the reception of an exteriorly threaded nut 6 by means of which the insulating body or core 2 and the casing 3 are firmly secured together. A suitable washer or packing 7 may be used between the shoulder 8 of the insulating core and the shoulder 9 of the casing.

Extending through the insulating body 2 is the electrode 9', which is provided with an enlarged tapered head 10 between which and the insulating body is located a suitable washer 11, and which electrode is secured in position by means of the usual nuts 12 and 13 turned on the threaded end of the electrode, and between which nuts and the insulating body are also located suitable washers 14. This terminal or electrode 9' is shown in the form of a rod projecting an appreciable distance beyond the end of the

casing. The other electrode comprises a coiled or spiral-formed member 15 comprising a plurality, or series of coils, the free end of which terminates adjacent to the end of the first electrode 9' while the opposite end thereof, which may be secured to the casing in any suitable manner, preferably terminates in a ring 16 of a size to fit tightly within the chambered casing 3, preferably adjacent to the end thereof, and may also be secured therein in any suitable manner. In the present instance it is shown as practically encircling the entire inner wall of the casing and then bent or doubled upon itself to extend adjacent to the electrode 10 to encircle the same in spaced coils. The spirally formed electrode 15 is provided with a sufficient number of coils to extend from the outer end of the electrode 9' to within the chamber of the casing 3, so that such coiled electrode extends a number of times around the electrode 9'. By this construction a large firing or sparking area is obtained without increasing the length of the plug body or of the electrode 9', which is a material advantage in the manufacture and efficiency of the plug. Not only this, but the present improvement avoids a fixed sparking point or points and so reduces to a minimum the danger of corrosion or burning and the loss of the sparking or firing efficiency. Furthermore, as the tendency of foreign matter is to follow the spiral to its base when the plug is placed in either a horizontal or vertical position in the engine cylinder, the accumulation of oil and carbon is thus avoided, so that a clean contact portion is maintained at the proper point. In addition, as a large firing or sparking portion is obtained it follows that any deposits of carbon or oil which may not follow the spiral to its base will not be sufficient to interfere with the operation of the plug and cause misfiring. In short, by the present improved form of plug the spiral electrode will tend to free itself from oil or carbon deposits and also provides a large area of sparking surface, thus prolonging the longevity of the plug to a considerable extent.

I claim as my invention:

1. A spark plug having an insulating body, a casing, and a pair of electrodes, one projecting beyond said body and the other spirally located around and throughout the

length of such projecting portion of the first electrode and having open spaces between the spirals.

2. A spark plug comprising an insulating body, a casing, and a pair of electrodes, one projecting beyond said body and the other consisting of a series of spaced coils located around and throughout the length of the projecting portion of the first electrode 10 and both having their sparking surfaces within the plane of the inner walls of said casing.

3. A spark plug comprising an insulating body, a casing, and a pair of electrodes, one 15 projecting beyond said body and the casing and the other comprising a continuous spirally wound member carried by said casing and consisting of spaced coils encircling the first electrode from the casing to the end 20 of such first electrode.

4. A spark plug comprising an insulating body, a casing, an electrode carried by said body and having a projecting part, and a spirally formed wire electrode having a 25 part inserted into and engaging said casing and having a series of spaced coils located around said first electrode and spaced therefrom and located within the plane of the walls of the casing.

30 5. A spark plug comprising a chambered casing, an electrode extending therethrough and insulated therefrom, and a spirally formed electrode comprising a series of coils located around said first electrode and 35 spaced therefrom and having an enlarged ring-formed base inserted within and engaging the walls of the chamber of said casing.

6. A spark plug comprising a chambered 40 casing, an electrode extending therethrough and insulated therefrom, and a spirally formed electrode comprising a series of coils located around said first electrode and spaced therefrom and having an enlarged 45 ring-formed base inserted within and engaging the walls of the chamber of said casing, said spirally formed electrode comprising an integral wire-formed member.

7. A spark plug comprising a chambered

casing, a rod-formed electrode extending 50 therethrough and insulated therefrom and projecting beyond the end thereof, and an integral wire-formed electrode comprising a series of coils spirally located around said rod and spaced therefrom and terminating 55 in an enlarged ring-shaped base secured within the chamber of said casing.

8. A spark plug comprising a casing, and a pair of electrodes, one comprising a 60 rod projecting beyond said casing and the other supported adjacent to the end of the casing and located spirally around said rod throughout the length of the projecting portion thereof and terminating adjacent to the end of said rod.

65 9. A spark plug comprising a body, a conductor wire mounted in said body and at one end projecting therefrom and forming a terminal, a spirally wound terminal secured to the body and encircling the aforesaid terminal in spaced relation thereto to provide a plurality of spaced coiled sparking surfaces arranged in spaced relation one above the other.

10. A spark plug comprising a body, a 70 terminal extending from one end of the body, and a second terminal secured to said body and consisting of a piece of conducting material coiled intermediate its ends to provide inner and outer spaced coils to embrace the first-named terminal in spaced relation to the latter.

75 11. A spark plug comprising a body, a conductor mounted in said body and at one 80 end projecting therefrom to form a terminal, a spirally wound terminal secured to the body and bent upon itself adjacent to its point of connection to the body and encircling the aforesaid terminal in spaced relation thereto to provide a plurality of 85 spaced coiled sparking surfaces arranged in spaced relation one above the other.

Signed at Cleveland, Ohio, this 30th day of December, 1911.

EDWIN C. HENN.
